UNITED STATES PATENT OFFICE.

EDWARD C. PERRY, OF WORCESTER, MASSACHUSETTS, ASSIGNOR TO AMERICAN CAR SPRINKLER CO., OF WORCESTER, MASSACHUSETTS, A CORPORATION OF MASSACHUSETTS.

CAR-SPRINKLER TANK.

1,040,401.

Specification of Letters Patent.

Patented Oct. 8, 1912.

Application filed May 21, 1910. Serial No. 562,595.

To all whom it may concern:

Be it known that I, EDWARD C. PERRY, a citizen of the United States, residing at Worcester, in the county of Worcester and 5 State of Massachusetts, have invented a new and useful Car-Sprinkler Tank, of which the following is a specification.

This invention relates to railway sprinklers and is particularly adapted for use on 10 electrical street railways.

The principal object of the invention is to provide means in the tank for preventing undue strains due to the flow of the water longitudinally in the tank.

15 Further objects and advantages of the invention will appear hereinafter.

Reference is to be had to the accompanying drawings in which—

Figure 1 is a side view of a tank constructed in accordance with this invention, parts being broken away to show interior construction. Fig. 2 is a sectional view on the line 2—2 of Fig. 1, and Fig. 3 is a horizontal longitudinal sectional view of the 25 same on a horizontal line above the bottom of the tank.

The tank 15 is shown provided with a bottom having a central low portion 16 having an outlet 17 therein and having sloping parts 30 18 extending up from this lower portion gradually to the ends of the tank. At one end of the tank, that is, at one of the highest portions of the bottom, is an inlet 19.

The tank is formed of sheet steel, preferably made up of pieces having riveted and caulked joints as is well understood in the art of boiler making. It is provided at one end with an open top man hole and at the other end with an open top pipe 21. The 40 pipe 21 is a vent pipe and is left open for the purpose of preventing the compression of the air at the end of the tank when the car goes down at that end and the formation of a vacuum when it goes up at that 45 end. In order further to avoid the ordinary effects of the rush of water back and forth in the tank, it is provided with splash plates 22 and 23. They are arranged vertically in

the tank between the center and one end and extend from the top to the bottom, thus 50 adding to the strength of the tank by anchoring the bottom to the top. They are arranged in transverse alignment across the tank but are spaced apart far enough so that a man can pass between them. 55

The plates 22 are between the center and one end of the tank and the plates 23 between the center and the other end. They are made so as to break joints, that is, each plate 23 is substantially opposite a space between two of the plates 22 and vice versa. In this way, the flow of water through the spaces between the plates 22 toward the plates 23 will be forced to divide and be divided part one way and part the other. 65 This effectually breaks up the direct currents of water from one end to the other and materially reduces the shocks of such a flow.

While I have illustrated and described a 70 preferred embodiment of the invention, I am aware that many modifications can be made therein by any person skilled in the art without departing from the scope of the invention as expressed in the claim. Therefore, I do not wish to be limited to all the 75 details of construction shown and described, but

What I do claim is:—

A water tank for a street sprinkler car, 80 made up of metal plates riveted together and provided with a plurality of rows of splash plates extending vertically from the bottom to the top and secured both to the bottom and top, said splash plates having 85 vertical spaces between them, the splash plates of one set being located substantially opposite the spaces between the splash plates of the next set.

In testimony whereof I have hereunto set 90 my hand, in the presence of two subscribing witnesses.

EDWARD C. PERRY.
